CARTON

Robert M. Dunning, St. Paul, Minn., assignor to
 Waldorf Paper Products Company, St. Paul,
 Minn., a corporation of Minnesota

Application June 2, 1945, Serial No. 597,269

6 Claims. (Cl. 229—37)

1

My invention relates to an improvement in cartons, wherein it is desired to provide a tight carton.

In the formation of cartons of the regular tubular glued end type, difficulty has been long experienced in providing a tight closure. The cartons are usually supplied the user in flat form glued along a longitudinal seam. In setting up the cartons it is usual practice to fold the same into tubular form and to seal one end over a mandrel or block which provides a tight seal for this end of the carton. After the carton has been filled, the second end thereof is then sealed. As there is no internal support for this sealing operation, the inner flaps, which are usually folded into opposed coplanar relation, are forced down into the carton, forming an ineffective seal with the overlying flaps forming the closure. This condition is aggravated by the fact that the flaps tend to curl when moistened with adhesive.

Various means have been provided for supporting the flaps during the sealing operation and much time and money has been spent in experimentation in an effort to obviate this previous difficulty. While various means have been provided to accomplish the desired result, many of these previous means require costly equipment or unusual carton design which require more stock or produces an unusual type of carton design which can not be sealed on regular sealing equipment.

It is the object of the present invention to provide means of supporting the inner flaps of the carton so that external pressure may be applied against the top of the carton to seal the flaps together without danger of folding the flaps inwardly. As a result the tight seal may be effected without the accompanying disadvantages.

A feature of the present invention resides in the provision of a means of supporting the inner flaps of the carton so that they can not curl inwardly when adhesive is applied thereto.

A further feature of the present invention resides in providing an innermost flap which acts to structurally support the remaining flaps to prevent the same from being forced or folded into the interior of the carton.

A further feature of the present invention resides in the provision of flap means connected to one of the closure flaps which acts in combination with the glue flap of the carton to support the remaining flaps of the closure.

These and other objects and novel features of my invention will be more clearly and fully set forth in the following specification and claims.

2

In the drawings forming a part of my specification:

Figure 1 is a perspective view of a carton having one end thereof in open position showing a means for preventing the inward warp of the closing flaps.

Figure 2 is a view similar to Figure 1 showing the innermost flap in closed position.

Figure 3 is a view similar to Figures 1 and 2 showing the carton in sealed form, a portion of the carton being broken away to show the inner construction thereof.

Figure 4 is a vertical section through the container showing the construction thereof.

Figure 5 is a diagrammatic view showing the blank from which the carton of Figures 1 to 4 is formed.

Figure 6 is a view similar to Figure 5 showing a modified form of construction.

Figure 7 is a perspective view of the carton shown in Figure 6 with one end thereof in open position.

Figure 8 is a view similar to Figure 7 showing the underlying flap of the end closure in partially closed position.

Figure 9 is a view similar to Figures 7 and 8 showing the carton in sealed condition, a portion of the carton being broken away to show the construction thereof.

Figure 10 is a vertical section through the carton showing the flap construction.

The carton A, illustrated in Figures 1 through 5 of the drawings, includes a series of wall panels 10, 11, 12 and 13 connected along parallel fold lines 14, 15 and 16. A glue flap 17 is connected to the panel 10 along a parallel fold line 19.

End closure flaps issue from the top and bottom edges of the various panels 10 through 13. The flaps 20, 21, 22 and 23 are connected to the panels 10, 11, 12 and 13, respectively, along the fold line 24. Similar flaps 25, 26, 27 and 28 are connected to the panels 10, 11, 12 and 13 respectively along the fold line 30. The various closure flaps described are designed to form top and bottom closures for the carton.

Connected to the closing flap 20 along a continuation of the fold line 19, indicated by the numeral 31, I provide a locking flap or tab 32. A second continuation 33 of the fold line 19 may serve to connect a second locking flap or tab 34 to the flap 25. It will be noted that the upper and lower ends of the glue flap 17 are provided with cut off corners 35 and 36. The adjacent ends of the tabs or flaps 33 and 34 are likewise cut diagonally at 37 and 38. These cut-off cor-

ners are designed to form mitered corners in the finished carton as will be best seen in Figures 1 through 4 of the drawings.

In gluing the carton blank of the carton A, it is necessary to either spot glue adhesive onto the flap 17 or else to apply a coating of printing ink or the like to the surface of the flaps or tabs 32 and 34 so that adhesive will not readily adhere thereto. The carton is then folded in the usual manner and the glue flap 17 adhered to the inner surface of the panel 13. In accomplishing this operation the panel 10 supporting the glue flap 17 is preferably folded along the fold line 14 and the panel 13 is next folded along the fold line 16 to overlie the glue flap and to be adhered thereto. This operation may be accomplished on any of the usual types of gluing machines.

The carton is then glued in tubular form and may be opened up into rectangular formation and one end of the carton sealed. As previously mentioned one end of the carton may be sealed over a mandrel and for this reason the flap 32 or 34 may be omitted from this first sealed end.

When one end of the carton has been sealed in the usual manner the carton appears as illustrated in Figure 1 of the drawings. The next step in the closing process is to fold the flap 20 downwardly into the position shown in Figure 2 of the drawings. It is usual practice to fold two flaps such as 20 and 22 into opposed coplanar relationship. In the present construction, however, the flaps 20 and 22 are sufficiently long to overlap slightly at the center, thereby making it desirable for the flap 20 to be folded down slightly in advance of the flap 22.

The flap 22 is next folded to slightly overlap the flap 20 and the remaining flaps 21 and 23 are next folded into super-imposed relation overlying the flaps 20 and 22. Adhesive is applied either to the undersurface of both flaps 21 and 23, to the upper surface of the flaps 20 and 22 and the undersurface of one of the flaps 21 and 23 or alternatively to both upper and lower surfaces of the outermost of the flaps 21 and 23. No special gluing apparatus is required and such a step as the gluing operation is conventional.

When the sealing flaps have been folded into sealed formation it will be noted that the diagonal cut edges 35 and 37 of the flaps 17 and 32, respectively, fold into abutting relation. At the lower end of the carton it will be noted that the diagonally cut edges 36 and 39 of the flaps 17 and 34 fold into abutting relation. The abutments of the diagonally cut edges acts to limit the folding of the flaps 20 and 25 about their fold lines 24 and 30, respectively, these edges acting to hold the flaps 20 and 25 in substantially right angular relation to the carton wall 10 from which they issue. As a result the amount of inward pressure necessary to seal the various flaps 20, 21, 22 and 23 and the various flaps 25, 26, 27 and 29 may be applied without danger of bending the inner flaps inwardly of the carton and forming an ineffective end seal.

The thickness of the stock forming the carton is exaggerated in the drawings for the purpose of illustration. It has been found in actual practice, however, that the abutment of the mitered edges described serves effectively to support the innermost flap 20, thereby permitting an effective top seal to be effected.

In Figures 6 through 10 of the drawings, I disclose a modified form of carton construction embodying similar principles. In the carton B shown in these figures, the carton blank includes

panels 40, 41, 42, and 43 connected along parallel fold lines 44, 45, and 46. A glue flap 47 is connected to the panel 40 along the fold line 49, which fold line is parallel to the lines 44, 45 and 46. Top closure flaps or panels 50, 51, 52, and 53 are connected to the wall panels 40, 41, 42, and 43 along the fold line 54. End closure flaps 55, 56, 57, and 59 are connected to bottom edges of the walls 40, 41, 42, and 43 along the fold line 60. The first mentioned flaps 50 through 53 are designed to lie in superimposed relation to form a top carton seal while the flaps 55 through 59 are designed to be superimposed to form a bottom carton end seal.

A continuation 61 of the fold line 49 serves to connect the flap 50 with a flange or flap 62. A similar extension 63 of the fold line 49 acts to connect the bottom closure flap 55 to the flange or flap 64. The flap 62 is defined by the fold lines 61 and 54 and the edge of the carton blank, while the flap 64 is bounded by the fold lines 60 and 63 and the edges of the carton blank.

A diagonal fold line 65 is provided in the glue flap 47 extending diagonally from the juncture of the fold lines 49 and 54. This fold line 65, together with the fold line 54 define a triangular panel 66 connecting the flap 47 with the flap 62.

A second diagonal fold line 67 extends diagonally from the juncture between the fold lines 49 and 60. The diagonal fold line 67 and the fold line 60 define a triangular panel 69 connecting the glue flap 47 to the flap 64.

In applying adhesive to the carton to secure the carton in tubular form it is necessary either to spot glue adhesive onto the panel 47 in the area between the fold line 49 and the adjacent edge of the blank, and between the diagonal fold lines 65 and 67. This may be accomplished either by applying glue on a spot gluing machine or by printing the outer surface of the flaps 62 and 64 as well as the triangular panels 66 and 69.

The application of printing ink or a different coating to the surfaces of these members acts to prevent the glue from adhering to these surfaces during the gluing operation.

In folding the carton B it is usual practice to fold the blank along the fold line 44 and then along the fold line 46 so that the marginal edge of the panel 43 overlies the glue flap 47 and is adhered thereto. One end of the carton may then be filled in the usual manner over a mandrel or the like. For this reason either the panel or flap 62 on the flap 64 may be omitted if desired. When one end of the carton has been sealed the carton appears as illustrated in Figure 7 of the drawings with the upper end thereof in open position. The carton may then be filled and the next step is to fold the upper closing flaps into superimposed relation.

In closing the upper end of the carton B it is usual practice to fold the flap 50 downwardly in the manner illustrated in Figure 8 of the drawings. In this operation the triangular panel 66 acts as a gusset connecting the flap 62 with the glue flap 47. The size of the triangular flap 66 and the angle of the fold lines by which it is connected to the panels 62 and 47 determine the limit to which the flap 50 may be pivoted. Accordingly if the angle between the fold lines 54 and 65 is approximately 45° or slightly less than this amount the flap 50 may pivot down into the horizontal position illustrated in Figure 9 and will be prevented from further pivoting. As a result the flap 50 is similarly supported extending at right angles to the carton wall 40 from

which it issues, acting as a firm foundation for the remaining flaps.

After the flap 50 has been folded into horizontal position the flap 52 is folded to overlie the same and the remaining flaps 51 and 53 are then folded into superimposed relation to overlie the flaps 50 and 52. External pressure may be applied to seal the flaps without danger of the flaps 50 and 52 warping down into the interior of the carton.

It will be noted that the carton construction illustrated utilizes no more stock than is ordinarily required for a glued end carton, as such a carton is always provided with a glue flap 17, the ends of which may be cut away if desired. Cutting off the ends of the glue flaps ordinarily does not save any paper stock, however, as this stock is wasted in the sheet. Thus a more effective seal may be effected without the use of any more paper than is usually required for the carton.

In accordance with the patent statutes, I have described the principles of construction and operation of my carton, and while I have endeavored to set forth the best embodiment thereof, I desire to have it understood that obvious changes may be made within the scope of the following claims without departing from the spirit of my invention.

I claim:

1. A carton comprising tubularly arranged side walls, end closure flaps issuing from said side walls, a glue flap on one of the side walls adhered to the inner surface of an adjacent side wall, a diagonally cut end on said glue flap, and flap means on the closure flap of said one side wall having an edge engageable against the diagonally cut end of said glue flap the diagonally cut flap end and said engageable edge of said flap means being at right angles when the said one side wall and its closure flap are in the same plane.

2. A carton comprising a series of connected side walls and a glue flap on one side wall overlapping the next adjacent side wall and secured to the inner surface thereof, end closure flaps on said side walls, and a flap on the end closure flap of said one side wall engageable against an edge of said glue flap to prevent the inward warping of said one closure flap, said engageable edges being at right angles when said one side wall and its end closure flap are in the same plane.

3. A carton including a series of connected side wall panels, a glue flap on one of said panels overlapping the adjacent panel and secured to the inner surface thereof, closure flaps issuing from said side walls, and a locking flap on the

closure flap of said one side wall having an edge thereof engageable with an edge of said glue flap, said engageable edges being at right angles when said one side wall and its end closure flap are in the same plane.

4. A carton comprising a series of panels foldably connected together, a glue flap on one of said panels overlapping the adjacent panel and secured to the inner surface thereof, closure flaps issuing from an end of said side walls, a flange on the closure flap of said one panel, and mitered edges on said flange and on said glue flaps designed to engage in abutting relation when said one closure flap is in closed position, said mitered edges being at right angles when said one panel and its closure panel are in the same plane.

5. A carton blank comprising a series of panels connected along parallel fold lines, a glue flap connected to one of said panels along a line parallel to said first named fold lines, flaps issuing from opposite ends of each of said panels, and a flange connected to one of said flaps along a continuation of the fold line connecting said glue flap to said one panel, and a diagonal notch between said flange and said glue flap having its vertex at the intersection of the fold line connecting said one flap to its supporting panel and the fold line connecting said glue flap to its supporting panel, the sides of said notch being arranged at right angles.

6. A carton including a series of connected panels, a glue flap on one of said panels overlying the adjacent panel and secured to the inner surface thereof, an obliquely cut end on said glue flap, closure flaps issuing from an end of said carton walls, the closure flap on said one panel having a flange thereupon provided with an obliquely cut edge thereupon engageable with the obliquely cut end of the glue flap, said obliquely cut edge on said flange and said obliquely cut end on said glue flap being at right angles when said one panel and its closure flap are in the same plane.

ROBERT M. DUNNING.
